UNITED STATES PATENT OFFICE.

VICTOR WEBBER, OF CLEVELAND, OHIO.

HINGE.

1,419,479.

Specification of Letters Patent. Patented June 13, 1922.

Application filed August 3, 1921. Serial No. 489,431.

To all whom it may concern:

Be it known that I, VICTOR WEBBER, a citizen of the United States, residing at Cleveland, in the county of Cuyahoga and State of Ohio, have invented certain new and useful Improvements in Hinges, of which the following is a specification.

My invention relates to improvements in hinges, and more particularly to that class or type used in temporarily adjusting and supporting doors during certain seasons of the year, as for example "screen doors," and the like.

The invention relates more particularly to an improved hinge mounting plate adapted to be permanently attached to the door frame or other suitable supporting wall at the side of the door opening and provided with independent hinge mounting and fastening elements whereby said hinge may be attached to or detached from said mounting independently of the fastening elements used in attaching the same to the frame or supporting wall.

The primary object of the invention is to provide a generally improved hinge mounting of the class indicated, which will be exceedingly simple in construction, cheap to manufacture, and efficient in use.

A further object is to provide a mounting plate having its face or hinge leaf supporting surface inclined toward the plane of the face of the frame and door to which the parts are attached and inclined toward the opposite hinge leaf whereby the latter will be normally inclined toward the plane of the face of the members to which the hinge leaves are attached so that when the door or hinge is in its closed position the spring in the hinge will tend to securely hold the door in seated or closed position, under the tension of the spring of the hinge.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a front elevation of a door equipped with a pair of hinges mounted and arranged in accordance with this invention.

Fig. 2, an enlarged plan view of a hinge and mounting attached.

Fig. 3, a cross sectional view taken on line 3—3 of Fig. 2.

Fig. 4, a plan view of the face side of the hinge leaf mounting plate, detached. 60

Fig. 5, a plan view of the under side of the mounting plate, detached.

Fig. 6, face and sectional views, respectively, of one of the adjustable hinge screw mountings or bushings, detached. 65

Similar numerals of reference designate like parts throughout all the figures of the drawings.

The hinge body 1, hinge leaves 2, and actuating springs 3 may be of any suitable 70 and convenient construction.

Referring to the improved hinge mounting, to which this invention particularly relates, it will be seen that I provide an improved hinge leaf mounting plate 4, adapted 75 to be initially attached to the door frame 5, or other suitable means of support through the medium of independent fastening elements 5^a, as shown most clearly in Fig. 1, of the drawings. 80

As a means of causing the hinge leaf 2, to be normally inclined toward the plane of the face of the mounting plate 4, as indicated by dotted lines in Fig. 3 of the drawings, when the hinge is not attached to a 85 door, and thereby causing the attached leaf spring when attached to a door to normally close and hold the latter in closed position under the tension of the hinge spring, the mounting plate 4 is provided with an inclined face 4^a, to receive the superposed hinge leaf, thereby normally inclining the opposite hinge leaf at an angle to the face of the supporting wall and attached door, as shown in Fig. 3, and causing the door 95 to be held firmly in a closed position.

As a means of enabling the hinge to be attached to the mounting plate 4, independently of the attaching elements 5^a, and the mountings of such plate, and to be likewise 100 independently detached therefrom, independent hinge fastening elements 6 are provided, said fastening elements or screws 6, being adapted to enter the usual screw receiving openings of the hinge leaf, and to 105 be fastened to the supporting plate 4, in any suitable and convenient manner, as for example, by means of adjustable screw receiving and mounting elements 4^b, having beveled sides and ends resting in correspondingly beveled or similarly inclined edges or under-cut sides 4^c, of openings 4^d. The open-

ings 4^c are preferably somewhat larger than the screw receiving blocks or mountings 4^b, so that the latter may be adjusted somewhat and the blocks 4^b are provided with threaded 5 openings 4^e to receive the independent hinge fastening elements 6. By adjusting the mounting elements 4^b in the openings 4^c thereby changing the relative location of the threaded openings 4^e therein, the inclination 10 or relative position of the hinges may be varied to correspondingly change the position of the door 7, when the latter is hung.

From the foregoing description, taken in connection with the accompanying drawings, 15 the operation and advantages of my invention will be readily understood.

Having thus described one of the embodiments of my invention, without having attempted to set forth all the forms in which 20 it may be made, or all the modes of its use, what I claim and desire to secure by Letters Patent, is,—

1. A hinge leaf mounting plate having an inwardly inclined face for the hinge leaf

whereby the opposite leaf of the hinge will 25 be normally inclined toward the plane of the base of said mounting plate when in closed position.

2. In a hinge, a hinge mounting plate having independent fastening elements and independent adjustable hinge mounting and fastening elements whereby said hinge may be adjusted and attached to or detached from said mounting plate independently of the mounting of said mounting plate. 30 35

3. In combination with a hinge including oppositely arranged hinge leaves, and independent fastening elements therefor, a mounting plate below one of said hinge leaves having its face inclined toward the 40 opposite hinge leaf whereby the latter will be normally inclined toward the plane of the face of the members to which the hinge leaves are attached when the hinge is closed.

In testimony whereof I have affixed my 45 signature.

VICTOR WEBBER.
